APPARATUS FOR MAKING PAPER CORD

Benjamin Milton Kimball, Gilman, Vt., assignor
to Millett Corporation, New York, N. Y., a cor-
poration of New York

Application June 4, 1940, Serial No. 338,688

2 Claims.

(Cl. 57—32)

This invention relates to improvements in paper cord and method of making the same.

Objects

Among the principal objects which the present invention has in view are: to provide an improved cord made of paper or the like; to provide means whereby cord may be made from a strip of continuous paper; to provide a method whereby minimum parts are utilized in the making of cord; to use a special solution for sizing the paper during the method of making cord therefrom; to employ a moisture resisting solution in the method of making the cord; to secure simplicity of construction and the method in making cord; and to obtain other advantages and results as may be brought out in the following description.

Drawing

Figure 1 is a diagrammatic view of the improved method of making cord and showing the successive steps utilized;

Figure 2 is a fragmentary portion of a strip of paper from which the cord is made;

Figure 3 is another portion of the paper and showing the same about to be twisted and in completed condition as a cord; and

Figure 4 is a fragmentary view similar to a part of Figure 1 and showing both sides of the strip wetted by the fluid.

Description

In the specific embodiment of the invention illustrated in said drawing, the reference numeral 10 designates a roll of paper from which a continuous strip 11 may be unwound as the method progresses. The strip feeds from the roll at its outer circumference and passes over suitable guides, such as pins or rollers 12, 13 for introducing the strip to the proximity of the surface 14 of a wetting fluid 15 carried by any suitable trough or container 16. In the upper part of this trough is situated a wetting roller 17 over which the strip of paper feeds, the structure being arranged to situate a lower part of said roller 17 within the fluid and an upper part of the roller above the fluid with the strip passing over the upper part of the roller so that the roller will transmit some of the fluid to the undersurface of the strip as the roller rotates and the strip advances in contact therewith. It will be understood that the roller may be suitably driven, and as one means of thus rotating the roller, the actuating force may be obtained by frictional contact of the strip therewith thereby impelling

the roller as the strip advances. Other means, however, for actuating the roller may be employed if desired. Some of the fluid will form a film on the roller as the cylindrical surface thereof rotates out of the fluid and into contact with the strip, and a wetting of the strip is accordingly accomplished by surface contact of the strip with the roller. Beyond the position where the strip leaves the roller is situated a doctor-knife 18 or other suitable means for scraping excess fluid from the undersurface of the strip and allowing such excess to drain back into container or trough 16. The strip is held in contact with the doctor-knife by suitable means such as a pin or roller 19 extending across the strip in proximity to the doctor-knife.

After the strip has passed beyond the doctor-knife and away from the container 16, said strip is longitudinally creased. This creasing may be obtained in suitable manner and in appropriate relation to the edges of the strip for obtaining desired double thickness of the strip after being folded. For instance, as indicated in the drawing, the edge margins are both doubled inward toward each other so the edges substantially meet at a central position or line 20. For the purpose of thus creasing the strip, the same passes over a suitable folder 21 which may be a rotatable wheel of appropriate peripheral width engaging the underside of the said strip at its middle portion. The strip edges crease downward at the sides of this folder 21 and are then folded inward by passing between power driven interfitting wheels 22, 23 of which one is grooved and the other peripherally ridged for both driving the strip with a continuous steady feed and for continuing the longitudinal folding of the strip as it feeds. As here shown, under wheel 22 is peripherally grooved, presenting a shallow V-shape in cross section, whereas upper wheel 23 provides a peripheral blunt ridge also somewhat V-shape in cross section to fit within the V-shaped part of the lower wheel. A scraper 24 engages within the groove of the under wheel 22, for keeping the groove clear of fluid or foreign matter, as will be understood by those skilled in the art.

The arrangement is such that the strip 11 is bent downwardly around the periphery of the lower wheel and proceeds to the twisting and winding mechanism. The strip is given a sufficient distance of travel from the said lower wheel 22 to the twisting and winding mechanism so as to afford opportunity for the now doubled strip to twist before reaching the twisting and winding

mechanism. When the strip is thus fed, as indicated accomplished at the right end of Figure 3, it constitutes the cord which is the resultant product of the present method. This twisted cord is designated by numeral 25.

The twisting and winding mechanism is here shown as comprising a vertical spindle 26 having thereon pulley 27 driven by a power driven belt 27'. The spindle extends above the pulley and receives a spool 28 thereon. Any suitable means may be employed for engaging the spool and spindle so as to positively rotate the spool by its support upon the spindle. It is here shown that this attachment is obtained by providing a key 29 longitudinally of the upper end of the spindle which is received in a corresponding key-way in the spool. The spool and spindle accordingly rotate simultaneously and preferably at a high rate of speed, for instance approximately 4500 revolutions per minute in the preferred operation of the apparatus. The spindle is preferable beneath the aforementioned grooved wheel 22 so that said spindle of the twisted cord 25 approaching the winding mechanism will extend in the same general direction.

A ring 30 is provided which is situated in substantially a horizontal position encircling the spool. This ring is shown mounted by means of a lever arm 31 extending downwardly away from the ring and pivoted at 32, the said lever being power driven to swing up and down at a considerably less rate of movement but synchronized with the rotation of the spindle so as to wind the cord back and forth on the spool as the cord winds around the spool.

Situated on the ring is a suitable rider or a traveler 33, which can continuously travel around the ring under actuating tension of the cord winding on the spool. While the traveler is relatively free to travel around the ring, there is sufficient friction present to keep it from rotating as fast as the spool. Since the cord passes through this rider and the rider is revolving around the spindle as an axis, the strip is twisted and the cord is thus formed as a tight twist. The greater number of revolutions of the spindle over the number of revolutions of the traveler will obtain the desired winding of the formed cord upon the spool and thus winding is accompanied by a feeding of the cord back and forth lengthwise of the spool by virtue of the up and down movement of the ring.

It may now be observed that the strip, in its progress from the wetting roller 17 to the twisting of the strip receives the wetting material on the underside of the strip and that the longitudinal folding is accomplished so as to fold the wetted side inwardly and thus leave the outer or exposed sides of the folded strip sub-

stantially dry. The fluid employed preferably is a suitable moisture resisting solution and preferably of a somewhat adhesive characteristic so the folded surfaces will tend to adhere after the cord is formed. Since the outer surface of the cord is substantially dry, there is no objectionable adhesion of the convolutions of the winding cord upon the spool. However, it is to be understood as within the scope of the present invention to fold the strip with the wetted side either inside or outside, and to fold it outside folder wheel 21 is placed above the strip instead of below it as shown, and the feeder wheels 22 and 23 are reversed in their relative positions so that grooved wheel 22 will be above and ridged wheel 23 will be under the strip. Furthermore, the contact of the folded strip by feeding wheels 22, 23 obtains a constant frictional drive for the strip and a desired tension on the portion of the strip between said wheels and spool so the winding upon the spool is tight and the difference in speed of feeding of the strip to the rate of feeding onto the spool will create the necessary actuation of traveler 33 around the ring. The strip employed is preferably paper, and it will be understood the invention is applicable to utilization of other materials if so desired.

Again, it is within the scope of the invention to apply the fluid to both sides of the strip. This is shown accomplished in Figure 4 where strip 11 passes over pin or roller 12 to the under portion of roller 17 to be carried below surface 14 of the fluid 15 in container 16. The strip leaves the roller 17 in an upwardly direction of travel to a roller 19 and thence to the folder as before. In its upward travel from roller 17, the strip may engage doctor knives 18, 18', on opposite sides thereof to remove excess fluid from both sides of the strip.

I claim:

1. Means for forming a twisted cord from a continuous strip, comprising means for effecting a preliminary longitudinal crease in the strip, other means for thereafter folding the strip edges inward, and means for twisting the folded strip into a cord.
2. Means for forming a twisted treated cord from a continuous strip, comprising means applying adhesive or the like to the strip, means effecting a preliminary longitudinal crease substantially at the middle of said strip, other means thereafter folding the strip edges inward, planetary means both twisting the folded strip and winding said strip on a spool, and a lever mounting said planetary means and reciprocating it in a direction longitudinally of the spool.

BENJAMIN MILTON KIMBALL.
